CABLEWAY LOAD CARRIER

Sam Samson, Stevenson, Wash.

Application October 15, 1934, Serial No. 748,353

6 Claims. (Cl. 212—109)

This invention relates generally to cableway systems, and particularly to a cableway load carrier.

The main object of this invention is the construction of a device for holding fast to a load that has been hoisted preliminary to being transported by an aerial cableway.

The second object is the construction of a device of the class described which will be simple to construct, positive in operation and independent of accurate manufacture for its successful operation.

The third object is to construct the mechanism in a manner that the load is always under full control and it cannot be accidentally lowered without first raising the load a short distance.

These, and other objects, will become more apparent from the specification following as illustrated in the accompanying drawings, in which:

Fig. 1 is a side elevation of the device showing the parts in position for the rope to descend or the cable being pulled up with the load.

Fig. 2 is a section taken along the line 2—2 in Fig. 5 showing the load line pulled all the way up with the tackle in a locked position.

Fig. 3 is a view similar to Fig. 2 showing the tackle in a partially broken position.

Fig. 4 is a section taken along the line 4—4 in Fig. 2.

Fig. 5 is an end elevation of the device.

Fig. 6 is a section taken along the line 6—6 in Fig. 2.

Fig. 7 is a section taken along the line 7—7 in Fig. 3.

Fig. 8 is a section taken along the line 8—8 in Fig. 2.

Fig. 9 is a section through the ferrule on the load line.

Similar numbers of reference refer to similar parts throughout the several views.

Referring in detail to the drawings, there is shown a common form of cableway 10 on which is mounted a carriage 11 which includes the wheels 12, a clevis 13 for the haul-back line 14, and a sheave 15 for the haul-in or load line 16 which may be operated by any suitable cable winding mechanism.

Attached to the sides of the carriage 11 are the straps 17 from which are suspended the cheek pieces 18 which are held in spaced relation by a tie bar 19 at the lower end thereof. The tie bar 19 has formed therethrough a throat 20 through which may freely pass the ferrule 21

which is permanently made fast to the load line 16 (as shown in Fig. 9) or in any other convenient manner. In this instance the line 16 is enlarged by the insertion of a pin 22, the ferrule 21 having been first slipped into position and then filled with zinc or other soft metal 23.

Between the upper ends of the cheeks 18 are mounted the two guide sheaves 24 between which the cable 16 is held, or is permitted to move when not otherwise prevented. Also supported by the cheeks 18 are the horizontal shafts 25 which pivotally support the depending arms 26 on whose lower ends 27 are formed the jaws 28 each of which has a semi-circular opening 29 which is approximately the diameter of the line 16.

Extending upwardly from the arms 26 are the toggle arms 30 between whose upper ends are disposed the toggle links 31 between whose forked ends 32 the line 16 freely passes through the opening 33. The links 31 are limited in their upward or locking direction by means of the stops 34 which are formed on the toggle arms 30. The arms 26 are urged apart by means of the springs 35 on the adjustable rods 36. Stop screws 37 are provided which limit the swinging movement of the arms 26 in either direction.

On each shaft 25 is mounted a pair of rocker arms 38 between which is placed a hub 39. The outer end of each pair of rocker arms 38 is connected by means of the slotted links 40 to a horizontal cross bar 41. Each bar 41 is connected at an intermediate point to a connecting bolt 42 of the toggle links 31. On the innermost end of each pair of rocker arms 38 is pivoted an angular latch 43 whose jaws 44 are urged toward a stop pin 45 by means of a spring 46.

The outermost ends of the arms 38 are urged upwardly by means of a spring 47 which re-acts against a lug 48 which is attached to the hub 39 of the arms 26 and 30.

The operation of the device is as follows: Assuming the parts to be in the position shown in Fig. 1 in which the line 16 is being lowered to pick up a load and that the load has been attached and the line is again being raised and the ferrule 21 has reached the position shown, the hoisting operation can be continued until the ferrule 21 engages the links 31, moving them to the position shown in Fig. 2. This, however, forces the jaws 28 to approach each other and prevent the ferrule 21 from again passing downwardly through the throat 20, the load being carried by the jaws 28.

Should it be desired to lower the load it is nec-

essary to hoist the line 16 sufficiently far to bring the ferrule 21 into contact with the jaws 44, causing same to rock the arms 38 pulling the bar 41 downwardly, thereby breaking the toggle links 31 and separating the jaws 28, after which the line 16 may be lowered since the ferrule 21 can now pass freely through the throat 20.

It can be seen from the foregoing that there is provided a positive means for holding a load in an elevated position where it will be locked and held as long as desired, regardless of the movements of the carriage 11, and that before the load can again descend it must be positively released by a lifting movement of the line 16.

15 It will also be observed that there is nothing intricate in the mechanism or the operation thereof, and no special degree of skill is necessary to successfully operate the device; nor can it be accidentally released and the load dropped, since 20 any movement which releases it makes it necessary that the load be supported by the hoisting drum, and therefore when the load is not being supported by the device it is being supported by the hoisting drum, making it extremely safe in its 25 operation.

I claim:

1. A cableway load carrier consisting of a carriage, a pair of cheek plates suspended from said carriage, a pair of pendent hinged arms mounted 30 between said cheek plates the lower ends of which have jaws formed thereon, a hoisting line passing over a sheave in said carriage and down between said jaws, said hoisting line having a ferrule fixed thereon adapted to pass between said jaws when separated or to be supported on the top side thereof when the jaws are closed, a toggle lever attached to each of said pendent arms, toggle links between the upper ends of said levers, yieldable jaw members in the path of said ferrule having operating connections to said toggle links whereby the upper travel of said ferrule against said yieldable jaws will break said toggle links and separate said first mentioned jaws.
2. A cableway load carrier consisting of a carriage adapted to operate on a standing line, a haul-back line for moving said carriage in one direction, a load supporting haul-in line passing over a sheave on said carriage, together with a pair of cheek plates suspended from said carriage having guiding sheaves at the upper end thereof and a throat piece at the lower end thereof through which said haul-in line can pass, a pair of pendent arms pivotally attached between said cheek plates, said arms having spring means for urging the lower end of same apart, each of said arms having an upwardly extending toggle arm, toggle links connecting the upper ends of said toggle arms, a ferrule on said haul-in line adapted to pass through said throat at the bottom of said cheek plates and to pass between said pendent arms when separated, rocker arms mounted on said cheek plates, each of said rocker arms having a spring-urged angular jaw pivotally mounted thereon in the path of said ferrule, and connecting means between said rocker arms and said toggle links whereby the upward movement

of said ferrule causing said toggle links to lock will cause said pendent arm jaws to approach each other on the under side of the ferrule for the purpose of supporting a load and whereby an upward movement of said ferrule from a load supporting position will cause said ferrule to engage said angular jaws and move said rock levers in a manner to break said toggle links and separate the lower ends of said pendent arms.

3. A cableway load carrier including a pair of spaced cheek plates having a pair of guiding sheaves at the upper end thereof and a spacer throat at the lower end thereof, a load line passing between said sheaves and through said throat, said load line having a ferrule thereon adapted to pass through said throat, hinged pendent arms on opposite sides of said line having jaws on the lower end thereof upon the upper side of which said ferrule can rest when the jaws are closed, toggle links between the upper ends of said pendent arms through which links the portion of said load line above said ferrule can pass, a cross bar whose intermediate portion is attached to said toggle links, rock levers supported by said cheek plates for actuating said cross bar, and a pair of angular jaws on opposite sides of said load line yieldably attached to said rock levers.

4. The device described in claim 3 in which the cross bar is joined to said rock levers by means of slotted links whereby motion can be transmitted from said angular jaws to said cross bar when said ferrule engages said angular jaws from the lower side thereof.

5. The device described in claim 3 in which said pendent arms are limited in their movements by lateral stops adapted to hold said load supporting jaws substantially in alignment with said guiding sheaves and throat.

6. A cableway load carrier consisting of a carriage adapted to operate on a standing line, a load line having a sheave mounted on said carriage and having the end thereof depending from said sheave, a load line having a ferrule thereon spaced from its load supporting end, a pair of cheek plates supported by said carriage having line guiding sheaves at the upper end thereof and a line guiding throat at the lower end thereof, said throat being large enough to permit the passage of said ferrule pendent arms on opposite sides of said line having line-engaging jaws at the lower end thereof and having a spring for urging said jaws apart, toggle arms extending upwardly from said pendent arms, toggle links connecting the upper ends of said toggle arms, said toggle links having the intermediate portion thereof surrounding said load line above said ferrule, a rocker arm coaxial with each pendent arm, each rocker arm having an angular jaw yieldably mounted on the inner end thereof and having a slotted link connected to the outer end thereof, each of said slotted links being attached to a transverse bar joined at an intermediate point to said toggle links, and spring means for urging said angular jaws and their attached rocker arms apart.
